UNITED STATES PATENT OFFICE.

ROCCO MANDALFINO, OF CLEVELAND, OHIO.

DESIGN FOR A SHOE.

Application filed March 8, 1924. Serial No. 8,873. Term of patent 14 years.

To all whom it may concern:

Be it known that I, Rocco MANDALFINO, a citizen of the United States of America, residing at Cleveland, in the county of Cuyahoga and State of Ohio, have invented a new, original, and ornamental Design for a Shoe, of which the following is a specification, reference being had to the accompanying drawings, forming a part hereof.

The figure is a perspective view showing my new, original and ornamental design for a shoe.

I claim:

The ornamental design for a shoe as shown.
ROCCO MANDALFINO.

Witnesses:

PAUL L. MILLER,
CARRIE M. SCOBELL.
